HANGER FOR ELECTRIC LIGHT FIXTURES

Isidore Wolar, 290 Collins Ave.,
Mount Vernon, N.Y. 11152

Filed Sept. 13, 1972, Ser. No. 288,520

Term of patent 14 years

Int. Cl. D8—08

U.S. Cl. D8—252

FIG. 1 is a side elevational view of a hanger for electric light fixtures in accordance with the invention,

FIG. 2 and 3 are top and bottom views respectively of the structure shown in FIG. 1, and

FIG. 4 is a perspective view of the hanger shown in FIG. 1 and taken in the direction of the arrow shown in FIG. 2.

I claim:

The ornamental design for a hanger for electric light fixtures, as shown.
